UNITED STATES PATENT OFFICE.

MILLARD EDWIN ALLEN, OF DANVILLE, KENTUCKY.

APPARATUS FOR CATCHING AND DELIVERING MAIL-POUCHES ON RAILWAY MAIL-CARS.

No. 889,084.

Specification of Letters Patent.

Patented May 26, 1908.

Application filed March 25, 1908. Serial No. 423,228.

To all whom it may concern:

Be it known that I, MILLARD EDWIN ALLEN, a citizen of the United States, residing at Danville, in the county of Boyle and State of Kentucky, have invented a new and useful Apparatus for Catching and Delivering Mail-Pouches on Railway Mail-Cars, of which the following is a specification.

This invention relates to apparatus for catching and delivering mail pouches on railway mail cars, and the objects of my improvement are, to catch a mail pouch and deliver one at the same time, certainty of catching and delivering, ease of operation, strength, and durability. These objects I attain by means of the apparatus illustrated in the accompanying drawings in which—

Figure 1 is a side elevation; Fig. 2, a plan view, with the top of the car removed at line A—B of Fig. 1; Fig. 3, a front elevation, showing the car partly in section; Fig. 4, a detail perspective view of the reversing mechanism; and, Fig. 5, a detail plan view of the catcher.

Similar reference numerals refer to similar parts throughout the several views of the drawings.

My improved catcher and deliverer consists essentially of two similar catchers 1 and 2, the catcher 1 being mounted on an arm 3, which extends from a stanchion 4, which in turn is pivotally mounted in brackets 5 attached to the door-frame of the car, and catcher 2 being mounted on an arm 6 extending from a crane post 7; and suspending-fingers, 8, extending from the rear of the catcher 1, and 9, supported by an arm 10 which extends from stanchion 4, for suspending the pouch to be delivered; and similar suspending-fingers for suspending the pouch to be caught on the train; finger 11, held by an arm 12 extending from crane-post 7; and finger 13, extending from the rear of catcher 2.

The construction of the catchers, which are similar in construction, is shown in Figs. 1 and 5 which show catcher 1. A main bar, 14, is provided, adapted to be secured upon an arm, 3 or 6. Two pivoted arms, 15 and 16, in the form of bell-crank levers, are pivoted at their fulcrum point 17 to bar 14 by a common rod or pin 18. The arms 15 and 16 are broadened and tapered from their forward ends to their rear ends and provided with an opening between their edges so as to admit bar 14 through the opening at pivot

point 17. The arm 15 is broader than arm 16 in order that arm 16 may pass through the opening in arm 15, and both arms are pivoted or hinged over bar 14 by the common pivot pin 18, so that the long, forward-extending arms 15 and 16 may be spread apart or brought together like the handles of a pair of tongs. Latches 19 and 20 are pivoted in arms 15 and 16 at 21 and 22 respectively in such a position that they may catch the shorter ends 23 and 24 of arms 15 and 16 respectively. Triggers 25 and 26, are pivoted in arms 15 and 16 at 27 and 28 respectively, and are adapted to be normally extended across the opening between arms 15 and 16 when the arms are separated. The shorter ends of triggers 25 and 26 extend beyond pivots 27 and 28 and are joined with latches 19 and 20 by means of links 27 and 28. It will be understood that by these means, when triggers 25 and 26 are placed in the same straight line across the opening between arms 15 and 16, the latches 19 and 20 are in position to engage parts 23 and 24, and when triggers 25 and 26 are pushed inward, as shown by the dotted lines (Fig. 5), latches 19 and 20 release parts 23 and 24. Flat springs 29 are secured on each side of bar 14 and extend forward, so that they press upon the outer side of arms 15 and 16 and have a tendency to close the outer ends of the arms together, as shown by the dotted lines. A buffer, 30, is provided on the front end of bar 14 and is pressed yieldingly forward by a spring 31. Bar 14 is preferably notched underneath (Figs. 1 and 4), in order that it may fit over its supporting arm 3 or 6, to prevent it swinging around and to keep it at right angles with its supporting-arm. A bolt, 32, (Fig. 4) secures bar 14 to arm 3, and a spring 33, under the head of bolt 32, presses bar 14 firmly into engagement with arm 3. When, however, it is desired to reverse bar 14, to reverse the catcher, bar 14 may be raised against the pressure of spring 33 until the notch in bar 14 is free from arm 3, when the catcher may be swung around until the notch again engages the arm in which position spring 33 will then firmly hold it.

Stanchion 4 is pivoted in upper and lower brackets 5, so that arms 3 and 10, extending therefrom, may be swung outward at right angles to the side of the car, or inward within the car. Brackets 34 and 35 are secured

to the outer side of the door-frame and extend over into the opening of the door in such a position that arms 3 and 10 just slide over them when the arms are swung out into 5 operative position at right angles to the side of the car. Spring catches, 36 and 37, are provided on brackets 34 and 35 and are connected by a vertical link, 38, in such a manner that when arms 3 and 10 are extended to 10 operative position catches 36 and 37 spring up behind them and hold them in the extended position. A pedal lever, 39, is pivoted to the door-post at 40, and to the vertical link 38 at 41. Thus the latches 36 and 37 may 15 be sprung down, so as to release arms 3 and 10, by placing the foot under pedal 39 and raising it. This system of brackets 34 and 35 and catches and pedal is provided on each side of the door, in order that the catcher 20 may be placed on either side to provide for running the car in either direction. A set of brackets 5 is also provided on each door post for the same purpose. A spring, 42, (Fig. 2) is attached to the inner wall of the car, by 25 one of its ends, and to a finger, 43, on stanchion 4. This spring has a tendency to swing arms 3 and 10 into the car when they are released from catches 36 and 37.

The usual crane-post 7 is placed at the station where the mail is to be delivered. From the top of this extends the arm 12, toward the track, and at some distance further down, the arm 6, parallel to arm 12. Arm 12 is provided at its free end with the oppositely-facing suspending-fingers 11, adapted to receive the ring on one end of a mail pouch. Each of the fingers 11 is provided with a spring, 44, which presses down upon the free end of the finger. The spring 44 30 prevents the ring from being slipped off the finger by ordinary forces, such as wind, but will release the ring when violently jerked by the moving catcher 1. The lower arm 6 carries the catcher 2 into which the pouch is delivered from the train. Catcher 2 is provided with a suspending finger 13 at its rear, and this finger 13 is also provided with a spring 45, similar to spring 44. Spring 45 is placed underneath finger 13.

50 The operation of the apparatus will now be readily understood. Let the train (Fig. 1) be moving in the direction of the arrow. The operator upon the train has spread arms 15 and 16 of catcher 1, suspended a pouch 46 on fingers 8 and 9 by pressing the rings of the pouch under their springs and has then swung the catcher 1 and pouch 46 thus suspended out the car-door until latches 36 and 37 have secured arms 3 and 10. At the station the mail clerk has suspended pouch 47

on fingers 11 and 13 by pressing the rings under their springs, and has spread the arms of catcher 2, in readiness for the approaching train. As the car passes crane 7, pouch 46 enters catcher 3, strikes triggers 25 and 26, thereby releasing latches 19 and 20, so that arms 15 and 16 come together and clasp the pouch, which now strikes buffer 30 and is firmly held in the grasp of the catcher. The buffer 30, with its spring 31, receives the impact, so that the pouch is arrested without destroying or injuring the crane. At the same time that pouch 46 is delivered, catcher 1 grasps pouch 47, strips it from fingers 11 and 13, holds it firmly, and carries it along. The mail clerk in the car now releases the latches 36 and 37, and the catcher 1 is automatically swung into the car by the force of spring 42, where the pouch 47 may be released from the catcher. It will be understood that there is no active element of danger to the operator in operating this apparatus, since he does not have to hold any part thereof while it is operating, nor expose himself outside of the car-door at any time, because all of the adjusting of pouches to be delivered and releasing pouches caught is done within the car.

Having thus described my invention, I claim—

1. A mail catcher and deliverer for railway post offices, comprising in combination with a car and a crane, a catcher on the car and a catcher on the crane, said catchers each comprising pivoted and bell-crank-shaped arms for receiving a mail pouch, latches pivoted in said arms to catch said arms and hold them in spread condition, and triggers pivotally mounted in said arms operatively connected with said latches to release said arms.

2. A mail catcher and deliverer for railway post offices, comprising in combination a car, a crane, swinging arms, a catcher on said car and a catcher on said crane, said catcher on said car being mounted on one of said swinging arms to swing out of and into said car, said catcher on said crane being mounted stationary thereon, said catchers each comprising pivoted arms which are spread to receive a mail pouch and held in the spread condition and closed by the mail pouch when it enters the catcher, means for suspending a mail pouch to be delivered on said swinging arms on the car, and means for suspending a mail pouch to be caught from said crane.

MILLARD EDWIN ALLEN.
